TABLE

Theodore W. Separa, 320 E. Breckenridge,
Ferndale, Mich. 48220

Filed Apr. 20, 1965, Ser. No. 84,882

Term of patent 3½ years

(Cl. D33—14)

FIG. 1 is a perspective view of a table embodying my design;

FIG. 2 is a top plan view thereof;

FIGS. 3, 4 and 5 are front and opposite end elevational views thereof as viewed along the lines 3—3, 4—4 and 5—5, respectively, of FIG. 2;

FIG. 6 is a sectional view thereof along the line 6—6 of FIG. 2; and

FIG. 7 is a perspective view of the underside thereof.

I claim:

The ornamental design for a table, as shown.
